UNITED STATES PATENT OFFICE.

CORNELIUS HARRIGAN, OF ROME, NEW YORK.

SLEIGH.

SPECIFICATION forming part of Letters Patent No. 278,662, dated May 29, 1883.

Application filed December 26, 1882. (No model.)

To all whom it may concern:

Be it known that I, CORNELIUS HARRIGAN, of Rome, in the county of Oneida, in the State of New York, have invented new and useful 5 Improvements in Sleighs, of which the following, taken in connection with the accompanying drawings, is a full, clear, and exact description.

This invention consists in improved devices 10 for securing the body of a sleigh to the forward end of the runners or dash-board frame thereof, and also in certain novel means for protecting the corners of a sleigh-body, all as hereinafter more fully described, and specifically set forth in the claims.

In the annexed drawings, Figure 1 is a perspective view of a cutter provided with my improvements. Fig. 2 is a full-size detail view of the device for connecting the body of the 20 sleigh or cutter to the forward end of the runners or dash-board frame of the same. Fig. 3 is a transverse sectional view of the means for protecting the top edge of the sleigh and forming a most durable bead on the same; and 25 Figs. 4 and 5 are side and plan views, respectively, of the corner-iron by means of which the corners of the sleigh-body are protected and braced.

Similar letters of reference indicate corresponding parts.

A denotes the body of a sleigh or cutter, mounted on the usual bracing or inclined standards or knees, which rise from the runners of the sleigh in the usual manner. The 35 forward end of the bottom B of the body A (which is usually made ascending toward the dash-board D, as shown) I secure to the runners r r by a metallic tie, T, consisting of an elongated plate, c, fitted to the side edge of the bottom B, and formed with an outward offset, d, terminating with a T-shaped end, e, which stands with its plane at right angles to the plane of the plate c, and is curved to fit the rear face of the forward end of the runner 40 r, which usually rises in front of the body A and carries the dash-board D. Said tie T is fastened to the bottom B and runner r by screws or bolts, as shown. By providing the top and bottom edges of the plate c with lips

f, lapping onto opposite sides of the bottom B, 50 said plate receives a more secure hold. The forward end portion of the sides of the body A is usually joined with the raised end portion of the bottom B and cut out rounding on the top, so as to facilitate the entry to the sleigh. 55 In order to protect the top edge of the body A, and to form at the same time a bead on the exterior of said edge, I attach thereto in the usual manner, flatwise, a band of iron or other metal of sufficient width to cover said edge 60 and project at the exterior thereof, as illustrated in Fig. 3 of the drawings. The corners of the body A, I protect by means of a metal plate, preferably of a right-angled-triangular form, so as to facilitate the fitting thereof to 65 the bottom of the sleigh. The greater or main portion of said plate is of the form of a trapezoid with perfectly plain surface, and devoid of the usual side flanges and spurs heretofore applied to similar corner-irons. The small 70 triangular corner b, adjacent to the shorter of the parallel sides of the trapezoidal section a, is raised and beveled on its upper side, as best seen in Fig. 4 of the drawings. Said corner-iron is countersunk in the bottom of the sleigh, 75 so as to come flush therewith, and the raised corner portion, b, of said plate is fitted to a correspondingly-beveled truncation of the corner of the sleigh-body, the corner-iron being secured in position by means of screws inserted 80 through holes in said corner-iron.

I do not claim, broadly, a metal plate applied to the corner of vehicle-bodies for the purpose aforesaid, as I am aware that the same is not new.

What I do claim as my invention, and desire to secure by Letters Patent, is—

1. In combination with the body and runner of a sleigh, the tie-plate T, consisting of the plate c, fitted to the edge of the bottom B, 90 and formed with the offset d, terminating with the T-shaped head e, standing with its plane at right angles to the plane of the plate c, the whole constructed and applied to the junction of the bottom B and forward end of the runner, substantially in the manner specified and shown.

2. The improved corner-iron for vehicle-

bodies, consisting of a metal plate formed with the plain flat main portion *a* and the raised triangular corner *b*, beveled on its upper side and fitted to a correspondingly-beveled truncated corner of a vehicle-body, substantially as shown and set forth.

In testimony whereof I have hereunto signed my name and affixed my seal, in the presence

of two attesting witnesses, at Rome, in the county of Oneida, in the State of New York, this 12th day of December, 1882.

CORNELIUS HARRIGAN. [L. S.]
